(57) **CLAIM**

We claim the ornamental design for vehicle, as shown and described.

DESCRIPTION

FIG. 1 is a front left side perspective view of a vehicle embodying my/our new design;

FIG. 2 is a rear left side perspective view thereof;

FIG. 3 is a front elevational view thereof;

FIG. 4 is a right side elevational view thereof; and,

FIG. 5 is a rear elevational view thereof.

The bottom view of the vehicle and the environmental background shown throughout the drawing views does not form any part of the claimed invention.
